G. H. REIN

RAZOR BLADE STROPPER

Filed Nov. 17, 1922

INVENTOR

Gottfried H. Reiss

Patented Nov. 13, 1923.

UNITED STATES PATENT OFFICE.

GOTTERIED H. REIN, OF CINCINNATI, OHIO, ASSIGNOR OF ONE-FOURTH TO JOSEPH BINDER, OF LUDLOW, KENTUCKY.

RAZOR-BLADE STROPPER.

Application filed November 17, 1922. Serial No. 601,444.

To all whom it may concern:

Be it known that I, GOTTERIED H. REIN, a citizen of the Republic of Switzerland, residing in Cincinnati, in the county of 5 Hamilton and State of Ohio, have invented new and useful Improvements in a Razor-Blade Stropper, of which the following is a specification.

This invention relates to a device for 10 stropping razor blades of either the double or single edged type, in which an object is to produce a stropping device adapted to permit of the rough and finish stropping to operation on both sides of each edge to be 15 stropped, without having to remove the blade from the device or to change the adjustment or relation of the parts of the device with relation to each other or the blade.

This and other objects are attained in the 20 device described in the following specification and illustrated in the accompanying drawing in which:—

Fig. 1 is a view of the device with its 25 parts in the positions they occupy during the stropping operation.

Fig. 2 is a fragmental side elevation of a portion of the device shown in Fig. 1.

Fig. 3 is a composite view of a detail of my invention.

Fig. 4 is a composite view of another 30 detail of my invention.

Fig. 5 is a fragmental view showing a modification of a detail of my invention shown in Figs. 1 and 2.

This invention, as I have shown it in Figs. 35 1 and 2, consists of a frame of relatively a heavy wire 6, which is in the form of a V, the point of the V being made of a series of spring loops 7, 8, and 9, loops 7 and 9 40 of which are in the form of coils while loop 8 is merely U shaped to leave a space 10 between coils 7 and 9. The action of the coils is that of an expanding spring which holds the frame branches 11 and 12 apart. This 45 spreading action is to hold a strop 13 in taut condition, the strop being mounted on the branches by means of loops 14 and 15. To prevent the strop from slipping upon the branches I provide friction rings 16 and 50 17 which hold it adjacent to the handles 18 and 19 which are mounted on the ends of the branches. Upon loop 8 I mount for pivotal and sliding action thereon a blade holder having a clip 20 which has apertures 55 21 and 22 in the branches 23 and 24 thereof

to permit such freedom of movement. An aperture 25 in the base 26 of the clip mounts the reduced end 27 of a rod 28 pivotally therein, the end being headed as shown at 29 to prevent disengagement from the clip. 60 Rod 28 is provided with a flattened portion 30 at the point where it crosses strop 13, two headed pins 31 and 32 being provided for receiving apertures 33 and 34 of a razor blade 35 which is to be stropped. A clamping plate 36, which has apertures 37 and 38 therein, is provided for placing it over the headed pins 31 and 32, slots 39 and 40, which extend from the apertures 37 and 38, having been provided for permitting the 70 plate being shifted to clamp the razor blade in position upon surface 30 of the rod. To permit the rod to be mounted I have provided a handle 41 attached to the end 75 thereof.

In the operation of the device the action of the spring loops causes the strop to be drawn taut so that the movement of the rod 28 in the arc of a circle will permit of the edges of the blade being brought into stropping contact with the surface of the strop. 80 In this movement but very slight rotative or pivotal movement of the rod will permit of an edge being stropped upon each forward and backward movement of the rod 28. 85 This operation takes place first over the rough side of the strop and then over the finishing side, the latter operation being carried out by swinging rod 28 and clip 20 through space 10 to the other side of the 90 strop.

In Fig. 5 I have shown a modification of the coiled spring shown in connection with the construction illustrated in Figs. 1 and 2, 95 in which there has been but one loop 42 provided.

To remove the strop the handles may be pulled from the ends of branches 11 and 12, when the looped ends of the strop may be slipped from the branches. To remove rod 28 and clip 20, one handle, as for example handle 18 may be removed, loop 14 of the strop slipped off the branch, friction ring 16 also slipped off, and the clip 20 slipped around the coils of loop 7 and off of the branch 11, the coils of loops 7 and 9 being separated for this purpose as shown in Fig. 2. The modification shown in Fig. 5, having but one loop 42, does not permit of the 105 swinging of the blade holder from one side 110

to the other of the strop. For this reason it is but necessary in this construction to remove the strop from one branch of the frame and to pass it to the other side of the blade holder in order to accomplish the result obtained by providing the space 10 described in the preferred construction.

Having thus described my invention what I claim is:—

10. 1. A razor blade stropper comprising a frame having two branches, a strop extending between the branches, and a blade holder adapted to be moved over the strop between the branches, said frame having means between the branches adapted yieldingly to

hold them apart and to mount the blade holder for movement between them.

2. A razor blade stropper consisting of a substantially V-shaped frame having a spring at the point of the V adapted to hold 20 the branches apart yieldingly, a strop between the branches and attached thereto, and a blade holder attached to the spring for movement thereon over the strop.

In witness whereof, I affix my signature 25 in the presence of two witnesses.

GOTTFRIED H. REIN.
